UNITED STATES PATENT OFFICE

1,925,931

STERILIZER VALVE

Joseph H. Okun, Brooklyn, N. Y., assignor to
Kny-Scheerer Corporation, New York, N. Y.,
a corporation of New York

Application November 21, 1931
Serial No. 576,463

5 Claims. (Cl. 167—3)

My invention relates to an improvement in a sterilizer valve and its novelty consists in the adaptation and arrangement of parts as will be more fully hereinafter pointed out.

sterilizing chamber by the operator as the contents of said sterilizing chamber are then thoroughly sterile and dry.

5 Surgical technique requires that all dressings, bandages, instruments, gloves, utensils and everything else used in connection with an operation and which may directly or indirectly come into contact with the open wound be positively sterilized.

10 This sterilization is effected in usual practice in a dressing sterilizer which has a cylindrical or sterilizing chamber entirely surrounded by an outer cylindrical chamber which is commonly known as the jacket. Suspended from the outer jacket there is an independent means for generation of steam or direct boiler steam may be run directly to said jacket.

My device has solved this problem and furnishes one valve which has an external dial indicator showing the position and position function of the valve at all times and which can be completely operated through the various positions by gradual rotation of the valve in one direction over the different positions of the dial indicator. This enables the operator to know exactly what steps have been completed and what step is next to be taken so that the operation is always carried out in a complete and uniform manner by means of my valve. All possible error is thereby eliminated in carrying out the process and the failure to perform any one of the successive steps is avoided as the operator always knows from the valve indicator what steps should be taken next as it clearly indicates what steps have been completed and the advancement is always in one direction, be it clockwise or counterclockwise. 80 85 90 95

In operating this usual and well known dressing sterilizer steam, which is specially generated or boiler steam, must be fed to the jacket and the air in the jacket must be expelled into the room or to a vent pipe. As the temperature of the water in the generator is raised to approximately 254° F. (the sterilizing temperature) there will be a further expellation of air from the sterilizing chamber due to expansion.

Referring to the drawings Figure 1 is a side longitudinal sectional view of a complete dressing sterilizer embodying my valve, being broken for convenience in illustration.

The steam in the jacket is now used for creating, by means of an ejector, a partial vacuum within the sterilizing chamber in order to insure penetration. The steam from the jacket is then allowed to flow directly into the sterilizing chamber and, because of the partial vacuum previously created therein as described, the steam will penetrate to the center of the dressings within said sterilizing chamber. The steam pressure within the sterilizing chamber is maintained at 17 to 18 pounds for a period of thirty minutes or more, depending upon the technique of the supervisor in charge. The steam in the sterilizing chamber is then allowed to escape either into the room or through a vent pipe, either by its own potential pressure or forcibly evacuated by means of the jacket steam through the ejector nozzle.

Figure 2 is a perspective of the valve casting and connections with the control handle and cover removed, showing the control handle connection in dotted outline and being in the first position.

45 the ejector nozzle.

When the sterilizing chamber gauge has registered zero the jacket steam is again ejected through the ejector nozzle to again create a partial vacuum of ten inches. The purpose of 50 this operation is to lower the boiling point of the water within the chamber, causing any condensation or dampness in the dressings to evaporate through the vent pipe into the open atmosphere. This drying process is aided by 55 the heat transmitted to the dressings from the adjacent walls of the sterilizing chamber shell. The jacket steam must then be conserved for the next sterilization process while the partial 60 vacuum within the sterilizing chamber must be broken to permit the opening of the door of said

Figure 3 is a perspective of the cover, control handle and connections of my valve showing certain portions in dotted outline also in position one as is shown in Figure 2. 110

Figure 4 is a back plan view of the operative disc control and operated by the valve handle and connections showing certain portions in dotted outline. 115

Figure 5 is a top plan view of the main body of the valve in the casting showing certain portions in dotted outline.

Figure 6 is a side elevation of my valve with a portion broken away and showing the internal 120

connecting passages in dotted outline as connected in control handle position two.

Figure 7 is a front elevation of Figure 6 showing the internal connecting passages in dotted outline.

Figure 8 is a side elevation of my valve similar to Figure 6 showing the internal connecting passages with the control handle set at position three.

10 Figure 9 is a front elevation of Figure 8 showing the connecting passages in dotted outline.

Figure 10 is a side elevation of my valve similar to Figure 8 with a portion broken away to show the internal construction and with the 15 internal connecting passages showing in dotted outline in accordance with the control handle in position four.

Figure 11 is a front elevation of Figure 10 showing the internal connecting passages in dotted 20 outline.

Figure 12 is a side elevation of my valve similar to Figure 10 showing the internal portions and connections in dotted outline and with the control handle set at position five.

25 Figure 13 is a front elevation of Figure 12 showing the internal connections in dotted outline.

Figure 14 is a side elevation of my valve similar to Figure 12 showing the internal construction and connections in dotted outline in accordance with the position of control handle in 30 position six.

Figure 15 is a front elevation of Figure 14 showing the internal connecting passages in dotted 35 outline.

Figure 16 is a side elevation of my valve similar to Figure 14 showing the internal construction and connections in dotted outline with the control handle in position seven.

40 Figure 17 is a front elevation of Figure 16 showing the internal connecting passages in dotted outline.

In the drawings 20 is a sterilizing chamber 45 entirely surrounded by a steam jacket 21 over which is rigidly mounted on the upper side a finishing jacket 22 in the usual well known manner. My control valve 23 is mounted in the usual airtight manner through the finishing jacket 22 into the steam jacket 21 and through pipe 24 which is also connected directly into the sterilizing chamber 20. A safety valve 25 of usual construction is connected through the finishing jacket 22 to the steam jacket 21 and the sterilizing chamber 20 and steam jacket 21 are rigidly secured at one end to casting 26 to 50 which is hingedly secured in the usual manner a safety steam locking door 27 of the usual construction used on such sterilizers and having the usual control handle 27a. A steam generator 28 of the usual construction used with this type of sterilizer is connected to the bottom of the steam jacket 21 by means of usual pipe connections 29 and 30 and the usual water pipe connection 31 running from a source of 55 water supply is connected to the bottom of the generator 28 and has the usual control valve 32. A pipe 33 running from a boiler or other source of steam supply is also connected to the generator 28 in the usual manner, running therethrough in a coil 34 and has the usual control valve 35 for controlling the same. A water gauge glass 19 having the usual connections 18 of regular construction is connected in the usual manner to the generator 28.

75 The valve 23 is comprised of its main casting

having the cup-shaped portion 80 with the external threading 81 over which is adapted to be threaded a cap 82 having internal threading adapted to engage the external threading 81. Said cap 82 has a tubular flange 82a which is externally threaded and has locking nuts 82b and 82c threaded over thereto. A shaft 83 is mounted through said cap 82 and flange 82a having a handle 84 rigidly secured thereto at 85 and a spring engaging member 86 integral with said handle terminating in a ball 87 adapted to engage pockets 88 which are numbered on the front dial of the cap 82, 1 to 7 in the clockwise direction as indicated in Figure 3. The positions 1 to 7 on the dial of cap 82 are each adapted to be marked with the functions of the device carried out by said particular position so that the operator will be fully informed of just what occurs at each of the seven positions of the dial control. On the inner end of the shaft 83 is rigidly secured a rectangular clamp member 89 which is adapted to fit over spring elements 90 which are rigidly mounted at their ends in pockets 91 in the front face of a circular disc 92 which is adapted to fit into 100 and rotate freely within the pocket 80.

The circular disc 92 has on its back surface (as shown in Figure 4) holes 55, 56 and 57 which run all the way through said disc and it has holes 50, 51, 52 and 53 which through 105 passageways are connected directly to the arcuate cut out 54 and holes 58 and 59 are connected together by a passageway.

The cup-shaped portion 80 has holes 38 drilled through the edge of the same connecting with 110 a passage 40 which leads to the steam jacket 21. Hole 39 (shown in Figure 7) also drilled through the edge of the cup-shaped portion 80 runs directly into passage 39b connecting directly to the steam jacket gauge 39a and on which the 115 steam pressure of the steam jacket 21 is registered throughout the operation of this device. Hole 43 drilled through the main body of the valve 23 connects up directly to the ejector 43a of usual construction (shown in Figures 6 and 120 8) and said ejector 43a is mounted in the body 23 at 43b by means of the usual threading and said ejector 43a terminates at its outer end into passageway 43c which leads to the outer air through the cap member 43d which is threaded- 125 ly connected at 43e to the body 23. Hole 60 drilled through the body 23 (as shown in Figures 8 and 9) runs through directly into opening 60a immediately around the ejector 43a. Hole 61 drilled through body 23 runs to the 130 passage through ejector 43a. Hole 62 drilled in the body 23 connects directly to the passageway 41 which leads to the sterilizing chamber 20 through the tube 24. Hole 63 drilled through the body 23 connects directly to passage 70 to 135 the sterilizing chamber gauge 70a which throughout the operations of my valve indicates the pressure or vacuum in the sterilizing chamber 20. Hole 64 is drilled through the body 23 and connects directly through passage 40 to 140 the steam jacket 21 so as to permit the escape of air therefrom.

As previously described, the turning of the handle 84 to place the registering spring pressure ball 87 in pockets 1, 2, 3, 4, 5, 6, 7 through 145 the clockwise turning of said handle gives us successively the different operating positions of the valve 23 and position 1 is shown in Figures 2 and 3; position 2 in Figures 6 and 7; position 3 in Figures 8 and 9; position 4 in Figures

10 and 11; position 5 in Figures 12 and 13; position 6 in Figures 14 and 15 and position 7 in Figures 16 and 17.

5 The turning of the handle 84, shaft 83 connected thereto and clamp 89 through its clamping over spring member 90, rotates the disc 92 together with its holes to the various positions required relative to the fixed position of the holes described in body 23 and shown in Figure 10 5, and we will now consider those seven positions and the respective positions of the enumerated holes of the disc 92 and the holes of body 23.

the body 23 and the steam will thence pass through the passageway 41 through tube 24 into the chamber 20 until a pressure of eighteen pounds has been built up and because of the vacuum previously created in the chamber 20 this steam will be drawn into the chamber 20 so as to penetrate every portion of the chamber 20 and thoroughly penetrate all tightly packed dressings even in the very center of said sterilizing chamber 20. Any condensation will be drained by means of a steam trap (not shown) in the usual well known manner.

In position 1 of the handle 84 hole 57 of the disc 92 is in alignment with hole 64 of the body 23 which makes a complete connection by the passages for air being driven out of steam jacket 21 as the generator 28 is set in operation by filling the same with water so that the displaced air within the generator 28 and steam jacket 21 is automatically taken care of and will pass off through the exhaust 64a, passing through passage 40 from the jacket 21 through holes 38 on to the front of the disc 92 so that it has free access to hole 57 which connects with the exhaust 64a.

When the handle 84 is turned to position 5 of the dial the steam being generated in the generator 28 and steam jacket 21 causes a pressure to be indicated on the steam jacket gauge 39a as the steam from the generator 28 passing through the passageway 40 passes to the jacket gauge 39a. The exhaust steam from the sterilizing chamber 29 will now pass through passageway 41, thence to body hole 62 into disc hole 52 through the arc 54 and into holes 60 of the body into the space 60a around the ejector 43a whence it will pass to the atmosphere through the passageway 43c. In this manner the steam

25 In position 2 of the handle 84 the water now being boiled in the generator 28 causes a pressure which is indicated on jacket gauge 39a by steam which passes from the generator 28 through pipes 29 and 30 to steam jacket 21 and thence through the passageway 40, then through holes 38 and 39 to jacket gauge 39a. The expanded air in the sterilizing chamber 20 will also pass through the tube 24, passageway 41 through hole 62 of the body 23 into hole 50 of the disc 92, thence through the arcuate passage 54 into hole 60 of body 23 to the space 60a around the ejector 43a. This position 2 gives us the indication of the steam pressure in jacket 21 on the 30 jacket gauge 39a and allows the expanded air in the sterilizing chamber 20 to pass off as the steam jacket 21 heats up the outer surface of the sterilizing chamber 20, said expanded air after reaching the space 60a passing off to the atmosphere through the passageway 43c. The steam in the steam jacket 21 will be built up until a pressure of eighteen pounds is attained. 35 40 45

from the sterilizing chamber 20 is evacuated therefrom by means of its potential pressure through the passageway 43c into the atmosphere until the steam pressure of chamber 20 is zero. 105

When the control handle 84 of my valve is turned to position 6 on the dial a partial vacuum of ten inches is created within the sterilizing chamber 20 for thoroughly drying the contents, said vacuum being maintained for a period of five minutes. The steam being generated in the generator passing through the steam jacket 21 causes a pressure to be indicated on the steam jacket gauge 39a as the steam from the generator passing through jacket 21 and the passageway 40 passes to the jacket gauge 39a. 110

The steam will enter disc hole 55 through body hole 61 out through the ejector 43a and the air in chamber 20 goes out through tube 24 into the body hole 41, thence through body hole 62 into disc hole 53 through arc 54 into body hole 60 and out into the ejector space 60a whereby the ten inch vacuum is created within the 115 120

In position 3 of the handle 84 the water being boiled in the generator indicates the pressure 50 on the jacket gauge 39a by the steam from the generator passing through steam jacket 21 and passageway 40 and hole 38 and hole 39 to the jacket gauge 39a. This steam also goes into hole 55 of the disc 92 and thence through body 55 hole 43 into ejector 43a creating a ten inch vacuum in the sterilizing chamber 20 whereby air is withdrawn through passageway 41 through the tube 24 from the sterilizing chamber 20 through the body hole 62 through hole 51 of the 60 disc through arc 54, thence out of hole 60 of the body 23 and out through the space 60a around the ejector. A ten inch vacuum is now indicated on the chamber gauge 70a as this drawing of the air also occurs through the duct 65 70 leading from the sterilizing chamber gauge 70a.

When the handle 84 is turned to position 7 of the dial the steam being generated in the generator passing through jacket 21 causes a pressure to be indicated on the steam jacket gauge 39a as the steam from the generator passing through the jacket 21 and passageway 40 passes to the jacket gauge 39a. The vacuum in the chamber 20 must now be broken in order to permit the opening of the door of the sterilizing chamber 20 and this is secured by allowing the air to enter 64a through body hole 64 into disc hole 58, thence through disc hole 59 entering body hole 63, thence through duct 70 to chamber gauge 70a and through passageway 41 into tube 24 and into chamber 20. This permits the passing of the air from the atmosphere by way of passages and holes as described into the inside of the sterilizing chamber 20, 125 38 41

In position 4 of the handle 84 the steam being generated in the generator 28 passing through steam jacket 21 causes the pressure to be indicated on the steam jacket gauge 39a as the steam from the generator passing through the passageway 40, holes 38 and 39, passes to the jacket gauge 39a. This steam is also admitted to the sterilizing chamber 20 through disc hole 56 which is now in alignment with hole 62 of 70 75 thereby breaking the vacuum and automatically permitting the easy and normal opening of the sterilizing chamber door 27 by turning the handle 27a in the usual manner. 14

valve handle 84 can be moved clockwise as described from position 7 to position 3 thereby immediately creating the partial vacuum within the chamber 20 as already described, so that 5 the process may be carried on through the successive positions 3 to 7 successively as hereinbefore set forth.

In carrying out the usual operation of this 10 dressing sterilizer through the seven positions as described it will be understood that when the generator 28 is filled with water in position 1 of the control handle 84 by means of opening valve 32 so as to permit the water to flow through pipe 31 into the generator 28 and the 15 air from the generator 28 and the steam jacket 21 have been allowed to escape as described, and the control handle 84 is turned to position 2, the generating power (not shown herein) will then be turned on to effect the heating of the 20 water in the generator 28 to make steam in the usual well known manner. This may be done also by opening the valve 35 and permitting steam to come in through the steam pipe 33 from a source not shown and passing through 25 coil 34 in the generator thereby effecting the heat in the generator in the usual manner.

It is also to be understood that the sterilizing 29 chamber 20 should be fully packed with the material to be sterilized before starting the operations as set forth in the positions 1 to 7 inclusive and at the completion of the sterilization on the completion of the operation described in position 7 of the control handle 84 the material sterilized in the sterilizing chamber 25 20 will be removed upon opening the door 27 by means of turning the handle 27a and the sterilizing chamber 20 repacked with material to be sterilized and the door 27 again closed and locked by means of handle 27a.

40 The process of sterilization will then be repeated but it will not be necessary to carry out the steps of positions 1 and 2 of the control handle 84 as these operations which are necessary at the beginning of the use of the sterilizer are now unnecessary as the generator 28 is filled with boiling water and the steam jacket 21 is filled with steam so that the sterilizer is in full operating condition and the control handle 84 can therefore be turned from the position 7 in the usual clockwise direction as described to 45 position 3. The operations of the sterilizer as described through the positions of the control handle 84 in positions 3 to 7 in succession will now be again repeated so as to sterilize the new material which has been packed into the sterilizer chamber 20.

It will be understood that many variations 50 may be made in the structure of my device without departing from the spirit and intent of the same.

I claim:

1. In a sterilizer valve a single valve control 55 adapted by rotation in one direction to a series of fixed and indicated positions to control the complete operation of sterilization, comprising a body having a group of holes and passages, different ones leading to an air exhaust, a sterilizing chamber pressure and vacuum gauge, a steam jacket gauge and an ejector and an outlet around said ejector, a disc adapted to fit said body and be rotated 60

said body and be rotated therein and having a group of holes adapted to be positioned in alignment with different holes in said body group and connecting also with different passages leading to a steam jacket, a sterilizing chamber and a generator. 80

2. In a valve a control handle mounted under spring tension terminating in a ball over a dial having position pockets and means indicating the different operations of each position of a series of said operative positions and said valve controlling said operations when in said described positions determined by said control handle, said valve comprising a body having a group of holes and passages, different ones leading to an air exhaust, a sterilizing chamber pressure and vacuum gauge, a steam jacket gauge and an ejector and an outlet around said ejector, a disc adapted to fit said body and be rotated therein and having a group of holes adapted to be positioned in alignment with different holes in said body group and connecting also with different passages leading to a steam jacket, a sterilizing chamber and a generator. 85

3. In a sterilizer valve a body having a group of holes and passages, different ones leading to an air exhaust, a sterilizing chamber pressure and vacuum gauge, a steam jacket gauge and an ejector and an outlet around said ejector, a disc adapted to fit said body and be rotated therein and having a group of holes adapted to be positioned in alignment with different holes in said body group and connecting also with different passages leading to a steam jacket, a sterilizing chamber and a generator, a cap covering said body and disc and carrying means for indicating the operative positions of said valve and a shaft running through said cap and means 90

connecting said shaft and said disc, an operative handle on the outer end of said shaft and means on said handle for engaging detaining means at said operative positions on said cap. 105

4. In a sterilizer valve a body having a group of holes and passages, different ones leading to an air exhaust, a sterilizing chamber pressure and vacuum gauge, a steam jacket gauge and an ejector and an outlet around said ejector, a disc adapted to fit said body and be rotated therein and having a group of holes adapted to be positioned in alignment with different holes in said body group and connecting also with different passages leading to a steam jacket, a sterilizing chamber and a generator. 110

5. In a sterilizer valve a body having a group of holes and passages, different ones leading to an air exhaust, a sterilizing chamber pressure and vacuum gauge, a steam jacket gauge and an ejector and an outlet around said ejector, a disc adapted to fit said body and be rotated therein and having a group of holes adapted to be positioned in alignment with different holes in said body group and connecting also with different passages leading to a steam jacket, a sterilizing chamber and a generator. 115
